CLAIM

The ornamental design for an outdoor speaker, as shown and described.

DESCRIPTION

FIG. 1 is a top, front, right side perspective view of a first embodiment of an outdoor speaker;
FIG. 2 is a bottom, front, right side perspective view thereof;
FIG. 3 is a bottom, front, left side perspective view thereof;
FIG. 4 is a top, rear, left side perspective view thereof;
FIG. 5 is a top view thereof;
FIG. 6 is a rear view thereof;
FIG. 7 is a right-side view thereof;
FIG. 8 is a left-side view thereof; and,
FIG. 9 is a front view thereof.

The broken lines in the drawings depict portions of the outdoor speaker that form no part of the claimed design.

1 Claim, 9 Drawing Sheets
